United States Patent Office.

E. N. WELCH, OF FORESTVILLE, CONNECTICUT.

Design No. 2,959, dated March 17, 1868.

DESIGN FOR A CLOCK-CASE SASH.

The Schedule referred to in these Letters Patent and making part of the same.

ALL WHOM IT MAY CONCERN:

Be it known that I, E. N. WELCH, of Forestville, county of Hartford, and State of Connecticut, have invented certain new and useful Improvements in Designs for Sash for Clock-Case; and to enable others skilled in the art to make and use the same, I will proceed to describe it, referring to the photographic drawings, in which the same letters indicate like parts in each of the figures.

In the accompanying photographic views, *a* is the upper member of plain round dial portion of the sash; *c* is a $\frac{3}{8}$ -eighth (plain moulded) octagon shape, or upper portion of the lower member of the sash; *d* are plain moulded straight sides of the lower member of said sash; *f* is a plain moulded bottom portion of the lower member of the sash, configurated at their united angles with rosettes, *h*.

What I claim, and desire to secure by Letters Patent, is—

The design for a sash for a clock-case, substantially as shown and described.

E. N. WELCH. [L. S.]
